UNITED STATES PATENT OFFICE.

ROBERT V. JONES, OF KANSAS CITY, MISSOURI, ASSIGNOR TO JOSEPH S. LOVERING WHARTON, WILLIAM S. HALLOWELL, AND JOHN C. JONES, COMPRISING A FIRM DOING BUSINESS AS HARRISON SAFETY BOILER WORKS, OF PHILADELPHIA, PENNSYLVANIA.

HEATER SYSTEM FOR LOCOMOTIVE SERVICE.

No. 906,031.

Specification of Letters Patent.

Patented Dec. 8, 1908.

Application filed January 3, 1908. Serial No. 409,175.

To all whom it may concern:

Be it known that I, ROBERT V. JONES, a citizen of the United States, and resident of and whose post-office address is 8745 5 Troost avenue, Kansas City, in the county of Jackson and State of Missouri, have invented certain new and useful Improvements in Heater Systems for Locomotive Service, of which the following is a specification, 10 taken in connection with the accompanying drawings, which form a part thereof.

My invention comprehends a system where a feed water heater conserves the thermal value in available exhaust steam, for the 15 purpose, among others, of furnishing hot water to stationary boiler plants, heating or drying systems or other various purposes, and supplying storage tanks with hot water for use in washing, filling or testing locomotive boilers or various other purposes. 20

The objects of my invention are, among others, to provide effective, economical and easily regulated means for accomplishing the ends herein described.

25 In carrying my invention into effect I preferably employ a feed water heater of the open type, in combination with an elevated tank, a pump for supplying water thereto, a pump for feeding water to stationary 30 boilers and a pump for furnishing locomotive boilers, or other points of use, with water at a given temperature under pressure, all of which are preferably arranged substantially as hereinafter described and, generally, as pointed out in the appended 35 claims.

In the accompanying drawings—Figure I is a general plan of a system involving in combination a feed water heater, 40 an elevated storage tank, and means for regulating the temperature of the water in said storage tank; also a boiler feed pump and details of connections which complete the system hereinafter more fully described.

45 Fig. II is a plan view of a service pump which receives water from the storage tank, and delivers it at a reduced temperature under pressure, to locomotive boilers for cleaning or other points of use. Fig. III is a 50 modification, showing the use of but one pump, which serves the purpose of conveying water to the storage tank, or direct to other point of use. Fig. IV is a further modification showing a feed water heater in com-

bination with two pumps and an elevated 55 storage tank, with means for maintaining water at a uniform temperature within the storage tank, one pump supplying the tank, and the other pump for supplying the boilers or other point of use. Fig. V is a further 60 modification showing the combination of a feed water heater and storage tank, and connections for supplying by gravity, water thereto; a pump and means for conveying the exhaust steam from said pump to the 65 heater. Figs. VI and VII are details respectively of the means employed for reducing the temperature of the water received from the storage tank, as shown in Fig. II.

Referring to Fig. I.—I employ a feed 70 water heater —1— of a well-known open type, in which the water is brought in contact with the exhaust from engines or generating units (not shown), being introduced into the heater through a suitable lead or 75 pipe —2—. It is manifest, however, that the exhaust steam may be supplemented automatically with live steam to cover such periods when the available exhaust steam is insufficient to heat the total amount of water 80 required, as shown particularly in Figs. III and V.

While I have described a heater of the open type, I would have it understood that I am not limiting myself to this particular 85 type of heater. On the contrary, any type of heater may be advantageously used in the system forming the subject matter of this invention without departing therefrom.

3— indicates a cold water main which 90 may, if desired, supply the water to the heater directly through leads or pipes —4— and —5—, controlled by float actuated valve —5^a—; the pipe —5— being arranged to discharge at a point in proximity to the top 95 thereof so that the water will be distributed over the heater trays, as is well-known and therefore not shown, or when air compressors, heating coils or similar devices are employed, the water may be discharged 100 therefrom and fed directly into the heater, in which event the piping arrangement for accomplishing this I have indicated at —6—7—8— and —8^a—. The supply pipe —4— is elongated to afford an overflow path 105 for the water from the main —3—; the length of the pipe being governed by the amount of pressure carried in the heating

system and friction in the pipes. The upper end of pipe —4— discharges into a pipe connection with the sewer. 9— indicates the main exhaust for the heater —1—, having located therein the back-pressure valve —10—. To the main exhaust —9— may be connected suitable piping communicating with a heating system; the lead or pipe —11— forming the induct to the heating system (not shown), while —12— indicates the educt, which is water sealed, through which is communicated the returns from the heating system to the feed water heater.

The connections for this heating system just described may be incorporated in the system as shown or may be dispensed with if desired.

13— is a suitable valve seated in the pipe —11— for admitting or cutting off supply to the heating system. Immediately above the back-pressure valve —10— of the main exhaust —9— and communicating with the feed water heater I provide a water sealed drip pipe —14—.

15— indicates a boiler feed pump which delivers the hot water received from the heater —1— through suitable piping —16—17— and —18— to the stationary boilers (not shown). The delivery of the water to the stationary boilers is insured by having the pump supply pipe —16— opening at a lower point on the heater than the opening —15^a—, through which the hot water is to be conveyed to a pump or other means which is to elevate or to flow hot water to a storage tank, hereinafter described.

I do not wish to be limited to the use of an elevated storage tank. It may be advantageous in some instances to use a storage tank on the same level with or below the heater, such as, for instance, shown in Fig. V, in which event I eliminate the use of the pump needed to force the water to the tank when elevated above the heater. However, I preferably use an elevated storage tank for the reason that I am thereby enabled to maintain the stored water at a given temperature by providing the circulating means hereinafter fully described.

19— is a thermometer located above the lead or pipe —16— to indicate the temperature of the water being fed to the stationary boilers. For storing a supply of hot water for filling, testing or washing locomotive boilers, a tank —20— is employed. This tank is usually provided with a vent —21— and glass gage —22— for preventing air logging of tank and indicating the quantity of water in the storage tank.

For forcing the hot water from the heater —1— to the elevated storage tank —20— I employ a pump —23— to which is connected, as shown, the leads or pipes —24— and —25— which form the path for the

water from the heater to the tank. The water when it leaves the heater —1—, it will be understood, is at a high temperature, approximately 210° F.; therefore, to insure the maintenance of the stored water within the tank at a proper uniform temperature, I provide means for carrying it back to the heater to be reheated when the water reaches a fixed level in the tank. This I accomplish by especially providing pipe or lead —26— which is connected within the storage tank —20— to a vertically arranged pipe —26^a— open at either end, the upper end extending above the water line. This arrangement insures the return of water to the heater from the lowest strata within the tank, and, therefore, that which is the coldest and which it is desired to reheat. The other end of pipe —26— is water sealed and connected to the heater —1— at a point near the top thereof, preferably opposite the cold water inlet. From this arrangement, it will be seen that the water of the lowest temperature in the storage tank is permitted to return to the heater —1— where it is reheated, whereupon it is again forced back into the storage tank —20— by means of a pump —23—. Through this continuous circulation, I maintain hot water in the storage tank at a substantially uniform temperature.

It is apparent that the hot water from the heater may be arranged to discharge direct from heater through lead or pipe —24— to pump —24^a— (see Fig. II), thence to locomotive boilers or other points of use and not from the storage tank —20— as described.

Valves —27— and —28— are located in the leads or pipes —4— and —16— which regulate the admission of cold water to the heater —1— and pump —15—, when desired, from the water main —3—.

Leading from the storage tank —20— is a pipe —29— which is connected with pipe —30— through which the water from the storage tank —20— is led to the locomotive boilers (or other points of use not shown). The pipe —30— is connected with a pipe —31— which communicates with a sewer pipe indicated at —32—. A gate valve —33— is provided in pipe —30— for permitting the water from the tank —20— to be drawn off into the sewer through the pipe —31—. It will be observed that the water is drawn from storage tank —20— through pipes —29— and —30— which provide a gravity distribution to the locomotive boilers or other points of use. It is manifest, however, that I may connect a pump to the lead or pipe —30— for the purpose of receiving the water and discharging it at a rapid rate into the locomotive boilers, or to other points of use, as shown in Fig. II.

For the purposes of washing or testing the locomotive boilers and for other uses, I pro-

vide means for reducing the temperature of the water drawn from the storage tank —20—. As the water in the storage tank —20— is at a high temperature—approximately 210° F.—it is necessary, in order to utilize this water for the purposes of washing and testing locomotive boilers, to reduce the temperature of it so as to prevent the possibility of scalding the workmen engaged 10 in this work. For this purpose, the temperature of the water is sometimes reduced to 125° F. I will now proceed to describe the manner in which I effect the lowering of temperature of the water for this service:—In Fig. II, a suitable pump —24^a— is provided and has communication with the elevated storage tank —20— through pipes —29—30— and —30^a—. The pump —24^a— is also connected with the cold water main 15 —3— through pipe —30^b—. Suitable check valves —31^a— and —31^b— are provided in pipes —30— and —30^b— to prevent the water entering the cylinder of the pump —24^a— being forced back through the pipes 20 —30— and —30^b—, thus confining its discharge through pipe —32^b— to the locomotive boilers or other points of use. A gate valve —35— is provided in pipe —30— for the purpose of directing and controlling the 25 flow of the water from the storage tank —20—. A similar gate valve —35^a— is provided in pipe —30^a— for cutting off the pump when necessary. The hot water enters the cylinder of the pump —24^a— through 30 pipe —30^a—, and the cold water through pipe —30^b— from the cold water main —3—. In the pipe —30^b— (see also Fig. VI) I provide a diaphragm controlling valve —32^a—. I also provide an automatic hot 35 water regulator —33^a—, Fig. VII, which is situated in pipe —32^b—, having communication with the pump cylinder. This hot water regulator regulates the temperature of the water being fed from pump —24^a— 40 through pipe —32^b— to the locomotive boilers or other points of use. I provide a pressure water pipe —33^b—, in suitable connection with any source of water pressure, not shown, connecting the hot water regulator —33^a— with the diaphragm controlling valve —32^a—. In the pipe —33^b— is located a drip connection —36^c—.

The hot water from the elevated storage tank enters the pump cylinder through pipe 45 —30^a—, and the cold water from cold water main —3— through pipe —30^b— and diaphragm controlling valve —32^a—, located therein. From the pump cylinder the water, the temperature of which has been reduced 50 through the admixture of the two waters just described, is forced through pipe —32^b— into and through the hot water regulator —33^a—. Within the hot water regulator —33^a— is located a thermostatic device 55 or tube —33^c— which lengthens by expansion

as the temperature of the water being fed therethrough rises (see Fig. VII), carrying with it rod —33^d— and causing valve —33^e— to open, which allows the water pressure connected to and passing through 70 pipe —33^b— and filling space —33^f— to flow through pipes —33^g— and —33^h— to diaphragm valve —32^a— (see Figs. II and VI). The pressure of the water on the diaphragm serves to open the valve —33ⁱ— and admit 75 more cold water from cold water main —3— through pipe —30^b— to be mixed with the supply of hot water entering the pump cylinder through pipe —30^a—. When sufficient water has been admitted to cool the 80 water to the proper temperature, the tube —33^e— contracts causing the valve —33^e— to close, thereby shutting off the water pressure from diaphragm of the valve —32^a—, and as the drip valve —36^c— is always 85 slightly open, the pressure on the diaphragm is reduced, thereby permitting the spring —33^j— to close the valve —33ⁱ— and cut off or reduce the supply of cold water to the pump cylinder. It will be readily understood from this that the valve —33ⁱ— is under the direct control of the thermostatic pipe —33^c— and that only the required amount of water will be admitted through 90 the valve to maintain the desired temperature at the outflow to the point or points of use.

A thermometer —34^a— is located on pipe —32^b— for indicating the temperature of water issuing from the pump cylinder. 100

It is readily understood that the automatic hot water regulator can be adjusted to vary the temperature of the water to any desired degree. To accomplish this adjustment a dial or index is provided on the surface —33^k— and a pointer —33^l— on the rotating spindle —33^m—. By rotating this spindle, the port —33ⁿ— is moved longitudinally into and out of registry with the port —33^h—, thus diminishing or increasing 105 the amount of pressure admitted to the diaphragm valve —32^a—. The rotation of the spindle also either increases or shortens the thermostatic rod —33^d—, thus causing the valve —33^e— to operate at the temperature 110 desired.

It is apparent that I need not necessarily take the water from the elevated storage tank as described, but may take it directly from the heater and deliver it into the cylinder of the pump —24^a— (see Figs. I and II). To accomplish this I provide a connection —24^a— connecting pipe —24— with pipe —30^a—. A valve —16^b— is provided in pipe —24^a— for controlling the 115 passage of water therethrough.

The operation of the pump —24^a— is automatic; control being established by means of a pump governor —36—. For example, when one of the nozzles or valves (not 120

shown) on the supply pipe —32^b— to point of discharge to the locomotive boilers or other points is open, the pump governor immediately starts the pump which is actuated by steam from any suitable source through lead or pipe —37—.

- Referring now in detail to Fig. III,—I illustrate a modification of the system, wherein the boiler feed pump —15— is employed for elevating the water to the storage tank or, when desired, to deliver the water at a rapid rate directly to the boilers. To accomplish this, I connect a pipe —18^a— to pipe —18—. A valve —18^b— is located in pipe —18^a— for the purpose of manually controlling the direction of flow of water delivered from the boiler feed pump —15—. 19^a— indicates the water relief valve, and —19^b— the pipe discharging into the storage tank —20—. 20^a— indicates an overflow opening in storage tank —20—. 20^b— indicates a discharge pipe through which the water is distributed to washing or drying machines or other points of use. The 25 exhaust from pump —15— is conveyed or delivered to the heater through pipes —21^a—, —21^b— and pipe —2—. 16^a— indicates a valve in pipes —16— and —17— leading to the pump —15—.
- 30 It may be advantageous to supplement the exhaust from both engines and pumps by a supply of live steam when the exhaust is not found sufficient to heat the feed water to the degree required.
- 35 22^a— indicates the pipe through which the supplementary live steam may be delivered to the heater. In this pipe is located the pressure reducing valve indicated at —22^b— for an obvious purpose.
- 40 23^a— indicates a drain or waste pipe connected with the lower portion of the heater —1—.

Referring now in detail to Fig. IV, I employ two pumps similar to the system illustrated in Fig. I. It will be noted that in both instances the boiler feed pump communicates with the heater at a lower point in the heater than the pump —23—, which elevates the water to the storage tank 50 —20—. This is important for the reason that it is absolutely necessary that the boilers have sufficient water; hence, with this arrangement, this service will always be assured of a supply. 23^b— and —23^c— indicate manually operated stop valves in pipes —17— and —26—. Stop valve —23^b— is employed for the purpose of cutting off the boiler feed pump; —23^c— for the purpose of cutting off the return of the water from the 55 storage tank —20— to the heater. It will be further noted that the water in the storage tank —20— is maintained at a given temperature, as a similar circulating means is here employed, the returns being taken from 60 the lower strata within the tank —20—

through pipes —26^a— and —26— to heater —1—. The gravity distribution of the hot water from tank —20— is made from pipe —20^b—, in which is situated a stop valve —24^a—.

As before stated, the storage tank may be situated on a level with the heater (see Fig. V), and in which event the water is supplied to the tank —20— from the heater —1— through pipe —25^a—.

25^b— and —25^c— indicate respectively suitable check and gate valve in pipe —25^a—.

21^a— indicates a manually operated valve in the pump exhaust pipe —21^b—. 21^d— 30 indicates a similar valve in the feed water pipe —17— to the pump —15—.

It is obvious that various changes may be effected in the construction and arrangement of the piping and other elements of the 35 systems herein described without departing from the spirit and scope of the invention.

Having thus described my invention, what I claim as new and desire to secure by Letters Patent is:

1. In a system of the character described, a feed water heater, an exhaust steam supply for said heater in combination with a boiler feed pump and a storage tank; means for circulating water through said heater 95 and said storage tank, substantially as described.

2. In a system of the character described, an open feed water heater in combination with an elevated storage tank; a pump for 100 supplying water thereto, a stationary boiler feed pump, and a service pump for receiving and conveying water from said storage tank, substantially as described.

3. In a system of the character described, 105 a feed water heater of the open type in combination with an elevated storage tank; means for feeding hot water from said heater to said tank; means for feeding hot water from said heater to stationary boilers; 110 and a cold and hot water service pump for feeding water from said tank at a lower temperature under pressure.

4. In a heater system, the combination of a feed water heater with a boiler feed pump; 115 an elevated storage tank; means for forcing water from said heater to said storage tank; means for maintaining the water in said storage tank at a substantially uniform temperature, and means for reducing the temperature of water fed from said tank for the purposes described.

5. In a heater system, the combination of a feed water heater with a stationary boiler feed pump; an elevated storage tank; means 125 for circulating hot water through said heater and said tank; a service pump suitably connected with said tank; and means automatically operating to reduce and maintain at a required temperature the water 130

issuing from said service pump, substantially as described.

6. In a heater system for locomotive service, the combination of a feed water heater with an elevated storage tank; means for feeding hot water from said heater to said elevated storage tank; means for maintaining the water in said elevated storage tank at a substantially uniform temperature, and 10 a service pump for feeding water from said elevated storage tank under pressure, substantially as described.

7. In a heater system, the combination of a feed water heater operating under the exhaust from engines, pumps or the like; a heating system supplied with steam from said heater; means for supplying cold water to said heater; an elevated storage tank supplied with hot water from said heater; 20 means for feeding the said water to said elevated storage tank; means for maintaining the water in said tank at substantially a uniform temperature; means for feeding hot water from said heater to stationary 25 boiler; and a gravity feed for the hot water from said elevated storage tank, substantially as described.

8. In a heater system, the combination of an open feed water heater operating under available exhaust; a heating system supplied from said heater; a cold water supply for said heater; means for regulating the supply of cold water to said heater; an elevated storage tank; means for feeding hot water 35 from said heater to said tank; means for returning the water from said tank to said heater so it will not fall below a certain temperature; and means for feeding water from said elevated storage tank to locomotive 40 boilers at a reduced temperature under pressure, substantially as described.

9. In a system of the character described, the combination of a feed water heater having an exhaust steam supply; a live steam 45 supply; a cold water supply and a heating system connected therewith; an elevated storage tank; means for feeding hot water from said heater to said tank; means for returning the coldest water in said tank to 50 said heater; an outlet pipe for said storage tank; a service pump connected to said pipe; a cold water supply communicating with said pump; and means automatically operating to regulate the temperature of the 55 water issuing from said pump, substantially as described.

10. In a system of the character described, the combination of a feed water heater having an exhaust steam supply; a live steam 60 supply and a regulated cold water supply; an overflow for said cold water supply; a heating system connected with said heater; a storage tank connected with said heater; a circulating pump connected with said

heater and said tank; a boiler feed pump 65 connected with said heater at a lower point than the said circulating pump connection; a valve controlled cold water supply for said boiler feed pump; a pipe connection leading from said tank to said heater for 70 circulating the water therethrough; a service pump connected with said tank; means for admitting cold water to said service pump; and means for automatically regulating the 75 temperature of water issuing from said service pump, substantially as described.

11. In a system of the character described, the combination of a feed water heater; a heating system connected therewith; a cold water supply controlled by a float actuated 80 valve, said cold water supply being discharged into said heater at a point in proximity to the top thereof; an overflow pipe for said cold water supply; the length of said overflow pipe being governed by the 85 amount of pressure carried in said heating system; an elevated storage tank; piping connecting said tank with said heater; means for circulating the water therethrough; means for draining said tank; and means 90 for cutting off said circulating means and delivering the water direct from said heater, substantially as described.

12. In a system of the character described, the combination of a feed water heater having an exhaust steam supply; a float controlled cold water supply; and a main exhaust; heating system connected with said main exhaust; a back pressure valve in said main exhaust; a drip pipe connected to said 100 main exhaust above said back pressure valve leading into said heater; an overflow pipe connected with said cold water supply; a pipe adapted to receive said overflow and convey the same to waste; an elevated storage tank; a pump; suitable piping connections between the heater, storage tank and said pump through which the water is caused to circulate; a vent in said storage tank; suitable piping leading from said storage 110 tank; a pump connected with said piping; a cold water supply in said pump; means automatically operating to reduce the temperature of the water delivered from said pump; and a boiler feed pump connected to said 115 heater, substantially as described.

13. In a system of the character described, the combination of a feed water heater and a pump; piping connecting said heater with said pump for the purpose of conveying the 120 hot water from said heater to the pump; a cold water supply to said pump; means automatically operating to reduce the temperature of the water issuing from said pump, substantially as described.

14. In a system of the character described, the combination of a feed water heater; a boiler feed pump and a service pump; means

automatically governing the temperature of water issuing from the said service pump; substantially as described.

15. In a system of the character described, 5 the combination of a feed water heater having an exhaust steam supply; a live steam supply; a float controlled cold water supply; an elevated storage tank; a pump; suitable piping connection between said heater and 10 said pump; piping connecting said pump with said storage tank; said pump adapted to force water received from said heater into said storage tank; a valve in the connection from said pump to said storage tank for 15 cutting off the storage tank; a water relief valve in said connection; a pipe for delivering the water direct from the pump to points of use, and a pipe for conveying the exhaust from the pump to the exhaust supply of the 20 heater; and a heating system connected with said heater, substantially as described.

16. In a system of the character described, the combination of a feed water heater having an exhaust steam supply; a supplementary 25 live steam supply and a cold water supply; a main exhaust; a heating system connected with said main exhaust; a back pressure valve in said main exhaust; a reducing valve in said supplementary live steam supply; a float controlled cold water supply; a storage tank; a pump for forcing water from 30 said heater to said storage tank; a vertical pipe within said storage tank; a pipe connecting said vertical pipe with said heater; a boiler feed pump connected to said heater; 35 check valves in both pipes connecting the two pumps with said heater, and a pipe leading from said storage tank, substantially as described.

40 17. In a system of the character described, the combination of a feed water heater; a storage tank, and a point of discharge; connections between the heater and the tank; connections between the tank and the point 45 of discharge; means for interrupting and regulating the communication between the tank, the heater and the point of discharge; means for circulating the feed water through the connections, substantially as described.

50 18. In a system of the character described, the combination of a heater; a reservoir and a point of discharge; connections suitably arranged between said heater, reservoir and point of discharge; controlled means intermediate the heater and the reservoir for directly connecting the heater with the point of discharge, substantially as described.

55 19. In a system of the character described, the combination of a heater, a reservoir and

a point of discharge; connections arranged 60 between the heater, reservoir and point of discharge; means for circulating the water through said connections; and means for regulating the temperature of the water issuing at point of discharge; substantially as 65 described.

20. In a system of the character described, the combination of a heater; a pump in communication with said heater; a cold water supply in communication with said pump; 70 a valve in said connection; an outlet to said pump; a hot water regulator valve in said outlet, substantially as described.

21. In a system of the character described, the combination of a feed water heater; a 75 service pump in connection with said heater; cold and hot water supplies in connection with said pump; diaphragm and check valves in said connection; an outlet to said pump; a hot water regulator valve in said 80 outlet controlling the operation of said diaphragm valve, substantially as described.

22. In a system of the character described, the combination of a feed water heater; a 85 service pump in connection with said heater; cold and hot water supplies; an outlet to said pump; means connected to said outlet, operating to govern the temperature of the water issuing through said outlet, substantially as described.

90 23. The combination, of a feed water heater, a reservoir; means for positively withdrawing the heated water from the heater; means for circulating water through the heater and the reservoir; independent 95 means for withdrawing water from the reservoir; and means for automatically regulating the temperature of the water so withdrawn.

100 24. The combination of a heater; an elevated storage tank; means for positively withdrawing water from the heater; means for circulating water through the heater and the tank; positive means for withdrawing heated water from the storage tank; means for varying the mixture of cold water with the heated water from the tank; and means for supplementing the water withdrawn from the heater by an increment of raw water, substantially as described.

105 Signed at Kansas City in the county of Jackson and State of Missouri this 30th day of Dec. 1907.

ROBERT V. JONES.
